UNITED STATES PATENT OFFICE.

FREDERICK J. SCHNEIDER, OF NEW YORK, N. Y.

SUPPORTER.

1,182,324.

Specification of Letters Patent.

Patented May 9, 1916.

Application filed October 27, 1914. Serial No. 868,817.

To all whom it may concern:

Be it known that I, FREDERICK J. SCHNEIDER, a citizen of the United States, and a resident of the city of New York, Middle 5 village, borough of Queens, in the county of Queens and State of New York, have invented a new and Improved Supporter, of which the following is a full, clear, and exact description:

10 This invention relates to stocking supporters and more particularly to improved means for increasing the elasticity of the supporter without increasing the effective length of the elastic element thereof, where- 15 by greater freedom in the movement of the limbs is provided for and tearing of the stockings obviated.

The invention further comprehends the provision of an improved stocking supporter 20 which includes a frame designed to take several folds of the elastic element of the sup- porter, whereby added resiliency or elasticity is provided for within a shorter compass or supporter length, so that the invention is 25 especially adapted for application where the distance between the body garment, such as a corset, and the stocking is at a minimum and so that the proper amount of elasticity neces- 30 sary under the special circumstances will be present.

With the above and other objects in view, the invention resides more particularly in the combination and arrangement of parts to be hereinafter more fully described, illus- 35 trated and claimed, it being an object to pro- vide an article which is simple, durable and efficient.

Reference is to be had to the accompany- 40 ing drawings forming a part of this speci- fication, in which similar characters of ref- erence indicate corresponding parts in all the views and in which—

Figure 1 is a perspective view of an im- 45 proved frame constituting a part of the stocking supporter; Fig. 2 is a vertical sec- tional view illustrating one method of at- taching the elastic to the frame to provide two folds; Fig. 3 is a similar view showing another method of applying the elastic in 50 which four folds are provided; Fig. 4 is a corresponding view for providing three folds; Fig. 5 is a similar view showing the method of producing five folds; and Fig. 6 is a fragmentary elevation illustrating the 55 application of the invention.

In carrying the invention into practice one application of the improved stocking supporter is shown, the supporter as a whole being indicated by the numeral 10 and comprising one or more elastic sections con- 60 nected to a body garment 11, such as a corset, and at the other end provided with a stocking engaging member 12 for attachment to a stocking 13. The supporter includes an elongated rectangular frame 14 having side 65 portions 15 and end portions 16, said frame being formed of metal or other suitable ma- terial to withstand considerable strain and provided at spaced points from each end with a pair of cross bars 17 slightly spaced apart in parallel relation to each other and to the end members 16 and at right angles to the sides 15. These cross bars are prefer- 70 ably of circular cross section so that the elas- tic section or sections may have free move- 75 ment thereover. One application of the use of the frame in producing a stocking sup- porter or the like is shown in Fig. 2 of the drawings in which a section 18 of elastic is adapted for attachment to the body gar- 80 ment and is extended in front of an end mem- ber 16 and between it and the adjacent cross bar 17 and at its free end is attached to the inner cross bar 17 as shown at 19, such as by passing the end of the elastic around 85 said bar and stitching the same as shown at 20. A section of elastic 21 carries the stock- 90 ing engaging member and is similarly at- tached to the frame in a reverse direction so that the two elastic sections overlap to pro- 95 vide two folds or lengths allowing greater elasticity than with a single section and per- mitting the elastic sections to slide between the ends and adjacent cross bars of the frame when strain is exerted thereon.

In Fig. 3 of the drawings the elastic sec- 100 tions are attached in the same manner except that in lieu of passing between the end mem- bers 16 and the adjacent cross bars 17, they are passed around the outer cross bar as shown at 22 and continued for another length for passage between said end mem- bers and the adjacent cross bars in the same manner. By this arrangement four lengths 105 of elastic are provided to increase the elas- ticity or resiliency of the supporter.

In Figs. 4 and 5 of the drawings the use of a single elastic section 23 is illustrated, in which one extremity thereof is adapted for attachment to the body garment in the 110

usual way while the other end carries a stocking engaging member. In Fig. 4 the elastic is shown passed between the upper end member 16 and the adjacent cross bar 5 and then downwardly between the lower cross bars under the inner one as shown at 24, and then upwardly between the cross bars at the top over the inner one as shown at 25, and downwardly between the lower 10 cross bar and the end member. In Fig. 5 the arrangement is the same with the exception that the extremities instead of being continued in opposite directions after passing between the end members 16 and the 15 adjacent cross bars are returned in opposite directions as shown at 26 and finally extended between said members and bars in such a manner as to provide five lengths or folds between the end members of the frame 20 as distinguished from the provision of three lengths or folds in the arrangement shown in Fig. 4.

It will thus be seen that provision is made for increased elasticity without increasing 25 the effective length of the supporter or usual elastic generally consisting of cloth covered rubber, and it will be obvious that when strain is exerted upon the elastic section or sections due to movements of the limbs, the 30 portions of the elastic constituting the folds or lengths within the area of the frame will give considerably more than would otherwise be possible and will slide over the cross bars and end members with such freedom as 35 to relieve the elastic of unnecessary strain with resultant prolonged period of use and

in such a manner as to obviate tearing of the garment or stockings.

Having thus described my invention, what I claim as new and desire to secure by 40 Letters Patent is:—

1. The combination with a rigid frame of substantially rectangular contour having sides and end portions and a plurality of rigid cross bars between the sides of the 45 frame and parallel to the ends thereof; of a plurality of folds of elastic material engaged with the end members and cross bars whereby resiliency in opposite directions from a fixed point is provided. 50

2. A supporter as characterized comprising an elongated rigid frame; and a plurality of lapped elastic members, each extending through said frame in guided relation thereto and projecting from the opposite ends thereof, the ends of said members being operatively connected. 55

3. A supporter as characterized comprising an elongated rigid frame; an elastic member mounted therein in guided relation 60 thereto, portions of said member being disposed in lapped relation within said frame and extended from opposite ends thereof for increasing the effective length of said member over the actual length of the device. 65

In testimony whereof I have signed my name to this specification in the presence of two subscribing witnesses.

FREDERICK J. SCHNEIDER.
